FLAMING ADVERTISEMENT

Filed Feb. 13, 1922

Inventor:

José de Elorza

UNITED STATES PATENT OFFICE.

JOSÉ DE ELORZA, OF MADRID, SPAIN.

FLAMING ADVERTISEMENT.

Application filed February 13, 1922. Serial No. 536,326.

To all whom it may concern:

Be it known that I, JOSÉ DE ELORZA, a subject of the King of Spain, and resident of Madrid, in the county of Madrid and State of Spain, have invented certain new and useful Improvements in Flaming Advertisements, of which the following is a specification.

This invention relates to flaming advertisements, in which on a frame, and properly secured, are fixed the letters forming the advertisement. The letters are hollow, transparent, of thick burnished glass, and by their form and colour will appear exactly like part of a burning log; that is to say, that through the sepia tone which imitates the bark, is seen the brilliant red of the fire, the latter being very prominent.

These letters, thanks to an adequate installation of electric bulbs which they contain, will be illuminated with varying intensity, the brilliancy alternately increasing and diminishing, so as to produce the effect of a burning log fanned by the wind. In order that the illusion, that the letters of the advertisement are burning, may be complete, they will be provided with extensive grooves, appropriately and artistically arranged, through which the simulated smoke will issue tumultuously. For this purpose, in the arrangement shown in the sketch, all the hollow letters of the advertisement will be in communication, by means of the different little jointed tubes which issue from each letter, with a large central tube, through which comes the steam from a steam-heating boiler, situated in any room of the building, on the roof of which the letters are fixed.

Thus the letters, whose form and colour, as has been said, are like those of a burning log, on being illuminated from inside, and enveloped in wreaths of steam to give the appearance of smoke (this smoke being in its turn illuminated by the red light of a reflector fixed at the base of the letters) will produce the disquieting sensation that

they are burning, thus attracting the most interested attention of the passer-by, who will wonder if it is an original advertisement or a real fire.

The working of the object of this invention is as follows: From the steam-heating boiler A issues the steam-collecting tube B which possesses the special feature of being closed at its extremity C and perforated with various circular orifices D (in the annexed drawing one only) in its sides. These orifices are connected by tubes J and connecting with the tubes J at E are tubes K which distribute the smoke belonging to each letter F. J is the tube for conducting the smoke from the accumulator B to the distributing tube E.

Thus the steam from the boiler, passing through the connecting tube, escapes through the openings in the said tube, passing directly through the pipes belonging to the letters, and issuing finally through the grooves corresponding to each letter.

The interior of each letter will contain several powerful electric bulbs I, suitably distributed. The intensity of illumination can of course be varied by using variously powered bulbs.

Having thus described my invention, what I claim is:

Improvements in advertising signs, comprising the combination of hollow letters of burnished glass, means for illuminating the interior with varying intensity, the various letters having the form of a log of wood, and being provided with orifices for the escape of steam, to simulate smoke issuing from the whole, forming a flaming advertisement.

Signed at Madrid, in the county of Madrid, and State of Spain, this 14th day of December, A. D. 1921.

JOSÉ DE ELORZA.
